UNITED STATES PATENT OFFICE.

LEWIS I. COHEN, OF NEW YORK, N. Y.

DESIGN FOR THE BACKS OF PLAYING-CARDS.

Specification forming part of Design No. 1,500, dated May 27, 1862.

To all whom it may concern:

Be it known that I, LEWIS I. COHEN, of the city, county, and State of New York, have invented or produced a new Design for the Backs of Playing-Cards; and I do hereby declare that the following is a full, clear, and exact description of the same, reference being made to the annexed drawing, making a part of this specification.

My design consists in the employment of four American shields, each with its appropriate number of stars and stripes, and placed on the two ends of the card in such relation to each other that whichever end be held upward the back will present always the same appearance. I arrange two of such shields at one end of the card, as at *a b* in the accompanying drawing, and on the other end two

other such shields *c d*, which are to be reversed in their positions in regard to the first two. In the center of the card is a single star *e*, and under each of the shields are olive branches crossed, as at *f*.

This design may be printed either in the red, white, and blue appropriate to the national emblem, or in gold, bronze, or other fancy style, or it may be in simple light and shade, as may be preferred.

I claim—

As a design for the back of a playing-card, the four national shields arranged in the manner substantially as described.

LEWIS I. COHEN.
